Michael A. Mann(57) **CLAIM**

The ornamental design for a rotisserie rack, as shown and described.

DESCRIPTION

1. Rotisserie rack

1.1 : Top

1.2 : Bottom

1.3 : Left

1.4 : Front

1.5 : Back

The parts, shown by means of broken lines, are not part of the claimed design; the right side view is omitted because it is a mirror image of the left side view (reproduction 1.3).
